UNITED STATES PATENT OFFICE

WILLIAM H. MOYSE, OF OSHAWA, ONTARIO, CANADA, ASSIGNOR TO GENERAL MOTORS RESEARCH CORPORATION, OF DETROIT, MICHIGAN, A CORPORATION OF DELAWARE

CRANK-CASE VENTILATION

Application filed June 6, 1927. Serial No. 196,839.

This invention relates to a crank case ventilator for an automobile engine.

It is the object of the invention to provide an improved ventilator for the engine crank case which will use suction obtained from part of the blast from the fan. More specifically it is the object of the invention to provide a ventilating device which will conduct the oil fog from the crank case through the cover for the valve rocker arms. This is a simple method of ventilating the crank case and has the advantage of utilizing the oil fog from the crank case for oiling the rocker arms.

Other objects and advantages of the invention will appear in the course of the following description, taken in connection with the accompanying drawing, and will be particularly pointed out in the appended claims.

In the drawing:

The figure is a side elevation of a conventional engine with parts broken away.

The numeral 10 indicates a conventional internal combustion motor and the numeral 12 the valve rocker arm cover. This cover is broken away at the left of the figure, disclosing the rocker arm mechanism. As the specific structure of the rocker arm mechanism is immaterial to this case, a detailed description thereof is unnecessary.

An oil filler inlet is indicated at 14 and connected to the side of this inlet is a flexible tube 16 leading to the opening 18 in the side of the rocker arm cover. If desired, an ordinary baffle plate may be placed over the forward side of the opening 18 to produce an aspirating effect. The cover is provided with an air inlet opening 20 at its front end. A similar opening 22 is provided at the rear end of the rocker arm cover and fixed in this opening is the flexible tube 24. This tube 24 extends down below the dust pan so that the fumes will not enter the car.

The operation of my device is as follows. Part of the air blast from the fan enters the opening 20 and passes along the cover through the opening 22 into the outlet tube 24, as indicated by the arrows. This creates a suction in the flexible tube 16 and a current of air is drawn from the crank case through the tube

16 into the cover 12. As the oil within the crank case is kept well churned while the engine is running, the air conducted through the tube 16 to the cover 12 is laden with fine particles of oil which keep the rocker arm mechanism well lubricated. In addition some fumes from the crank case enter the rocker arm cover through the usual tappet rod openings.

What I claim is:

1. In an internal combustion motor having a crank case and overhead mechanism, a cover for said mechanism, an outlet leading from the rear end of said cover, an opening in the front end of said cover, and a conduit from said crank case to said cover.

2. In an internal combustion motor having a crank case and overhead mechanism, a cover for said mechanism, an outlet leading from the rear end of said cover, an opening in the front end of said cover, and a conduit leading from said crank case to a point on said cover adjacent the front end.

3. In an internal combustion motor having a crank case and overhead mechanism, a cover for said mechanism, an outlet leading from the rear end of said cover, an opening in the front end of said cover, a removable oil filling inlet in said crank case, and a flexible conduit between said oil filling inlet and said cover.

4. In a structure as recited in claim 3, said conduit being connected to said cover adjacent the front end.

5. An internal combustion engine having a crankcase, an overhead valve mechanism, a cover for said mechanism forming a valve compartment, a passage establishing communication between the crankcase and the compartment for supplying oily vapors to the valve mechanism, said cover being provided with spaced air intake and discharge openings, and means for passing a stream of air into said compartment through said intake opening and out through said discharge opening, said stream exerting an aspirating effect on the passage to withdraw vapors from the crankcase.

6. An internal combustion engine having a cooling fan, a crankcase, and a valve com-

partment, a passage establishing communication between the crankcase and the compartment for supplying oily vapors to the valve mechanism, said compartment being provided with an opening adjacent its forward end arranged to receive a portion of the fan blast, and with an opening adjacent its rear end for the discharge of the air stream, said passage being arranged so that it is subject to the aspirating action of the air stream passing through the compartment to withdraw vapors from the crankcase.

7. An internal combustion engine for automobiles having a crank case, an overhead valve mechanism, and a cover for said mechanism forming a valve compartment, a passage connecting the crankcase and the valve compartment for conducting oily vapors thereto, and a suction tube mounted on said cover and leading from said compartment to a point beneath the car where it is subject to the aspirating action of the passing air currents to apply suction to said compartment to remove vapors therefrom.

8. An internal combustion engine for automobiles having a crank case, an overhead valve mechanism, and a cover for said mechanism forming a valve compartment, a passage connecting the crankcase and the valve compartment for conducting oily vapors thereto, and a suction tube mounted on said cover and leading from said compartment to a point beneath the car where it is subject to the aspirating action of the passing air currents to apply suction to said compartment to remove vapors therefrom, said engine being provided with the usual cooling fan and said cover being provided with an opening adjacent its forward end to receive a portion of the fan blast, said blast assisting the aspirating action on the suction tube.

In testimony whereof I affix my signature.
WILLIAM H. MOYSE.
